[57] CLAIM

The ornamental design for a toy pin-ball machine, substantially as shown and described.

DESCRIPTION

FIG. 1 is a front top perspective of a toy pin-ball machine showing my new design, also showing one side; FIG. 2 is a bottom perspective thereof, also showing the rear;

FIG. 3 is an elevation showing the side not visible in FIG. 1;

FIG. 4 is a bottom view thereof; and

FIG. 5 is a side elevation showing another position.
